UNITED STATES PATENT OFFICE.

CARL FREEMAN BLEDSOE, OF CHICAGO, ILLINOIS, ASSIGNOR TO OGLE CONSTRUCTION COMPANY, A CORPORATION OF ILLINOIS.

SAFETY MEANS FOR HOISTS AND THE LIKE.

Application filed June 19, 1926. Serial No. 117,024.

This invention relates to safety means with reference to apparatus in which the load is moved by a cable and concerns itself with mechanism for sustaining the load in 5 case the cable breaks.

The invention comprises the novel structure and combination of parts hereinafter described and more particularly pointed out and defined in the appended claims.

10 In the accompanying drawings which illustrate a preferred embodiment of this invention and in which similar reference numerals refer to similar features in the different views:

15 Figure 1 is a diagrammatic view of a hoisting apparatus embodying oppositely moving buckets involving this invention.

Figure 2 is a diagrammatic view of parts 20 of a hoisting apparatus in which a single bucket is used, involving this invention.

Figure 3 is a fragmentary elevational view of the safety means involving this invention.

Figure 4 is a top plan view of the structure shown in Figure 3.

Figure 5 is a sectional view upon the line V—V of Figure 3.

This invention in its broadest aspects 30 comprises a plurality of movable members which may be in the form of a pair of buckets, receptacles, cars or the like, or one of which may constitute a counterweight; and means including cables for moving the same, in combination with means independent of 35 said cables for sustaining said members in case a cable fails by breaking or tearing apart or the like. As the invention is very useful in connection with hoisting apparatus, I have illustrated the application there- 40 of in connection with a hoisting apparatus.

Referring to Figure 1, there is shown a hoisting machine 1 which may be of the type disclosed in my copending application, Serial No. 46,621, filed July 28, 1925, and 45 which embodies a drum 2 and slack arms 3. Cables 4, which are attached to the drum, extend over a guide drum or pulley 5. From the pulley 5, one cable extends over the load supporting pulleys 6 and 7, and 50 is attached to a coal or ash hoisting bucket 8 by a suitable bail 9; the other cable is trained over a pulley 10 and is attached in a similar way to a similar bucket 8. The cables 4 are attached to the drum 2 in such

a manner that one will wind up and elevate 55 one bucket and the other will unwind and lower the other bucket as the drum is rotated. The mechanism so far described is old and well-known and for this reason it has been only diagrammatically illustrated. 60

In the operation of such a hoisting apparatus, the cable 4 that sustains the loaded bucket sometimes fails, that is, it breaks, whereby the loaded bucket drops. This has proven objectionable. This invention while 65 not restricted to hoisting apparatus has been designed to remedy such a defect.

In the embodiment that is chosen to illustrate this invention, a flexible connection or cable 11, which has its ends attached to the buckets 8, is trained over a pair of pulleys 12 mounted upon a stationary support 13 above the buckets. An intermediate portion of this cable extends between the pulleys 12 in the form of a loop 14. A pulley 15 is supported in this loop and is freely movable in a vertical direction. Guides 16 are preferably provided for guiding the pulley 15 and confining its movements in a vertical direction. The guides 16, which are preferably of channel shape in cross section, engage the side strips 17 of a rectangular frame or block 17^a in which the pulley is journaled. A counterweight 18^a is suspended from the pulley block to maintain the same in vertical position. 85

The aforementioned support 13 consists of a pair of parallel members 13^a as shown in Figure 4. A brake shoe 18 is pivoted to the inner side of each member 13^a adjacent each pulley 12 for engagement therewith. A link 19 is pivoted to each brake shoe. The lower ends of the links are pivoted upon a common pivot pin 20 in an abutment block 21 adapted to be engaged by the pulley block 17^a when the pulley 15 is elevated as will hereinafter be more fully explained. 95

In Figure 2, there is illustrated an apparatus in which a counterweight displaces one of the buckets. In this instance one end of the safety cable 11 is attached to the bucket 8 while the other end is trained under a pulley 23 on the counter weight 22, and is attached to a stationary support 24. One operating cable 4 is attached to the bucket 8 and trained over the pulley 10, while the other cable 4 is attached to the stud 24 and trained under the pulley 23 and over the 100 105

pulley 6. The other ends of these cables 4 are adapted to be attached to the drum of the hoisting machine.

In operating the apparatus herein explained, the hoisting machine, which automatically reverses itself, will alternately raise and lower a bucket, the other bucket or counter weight 22 will of course move in the opposite direction. Now assume that 10 one of the cables 4, especially the one that sustains the load, should fail whereby the loaded bucket is released. The weight of such bucket will be immediately sustained by the safety cable 11. This weight on the 15 safety cable will elevate the pulley 15 for applying the brakes 18 and stopping rotation of the pulleys 12. The friction between the cable and pulleys will prevent the cable from sliding, so that the load will be 20 held suspended from the safety cable. This will prevent injury arising through a falling load to either the bucket or a workman.

I am aware that many changes may be made, and numerous details of construction 25 may be varied through a wide range without departing from the principles of this invention, and I therefore do not purpose limiting the patent granted hereon, otherwise than necessitated by the prior art.

30 I claim as my invention:

1. In an apparatus of the class described, a pair of oppositely movable members, a hoisting machine comprising a drum, cables connecting said members and drum, sheaves 35 for supporting said cables, a pair of pulleys supported above said members, a cable trained over said pulleys and attached to said members and means for braking said pulleys when either of said first mentioned 40 cables fail.

2. The combination with a hoisting machine including a drum, a pair of receptacles having cable connections with said drum, and means for sustaining said receptacles if a cable connection fails, comprising a cable attached to said receptacles, pulleys for supporting said cable, and means set in motion by said cable for braking said pulleys when a cable connection fails.

45 3. In an apparatus of the class described, a support, a pair of pulleys mounted upon said support, a cable trained over said pulleys, receptacles attached to the ends of said

cable, an intermediate portion of said cable extending between said pulleys in the form 55 of a loop, a movable pulley supported in said loop, brakes for said first mentioned pulleys and means carried by said last mentioned pulley for applying said brakes.

4. In an apparatus of the class described, 60 a support, a pair of pulleys upon said support, braking means for said pulleys, a movable pulley, a cable trained over said pulleys, and means carried by said movable pulley for applying said brakes. 65

5. In an apparatus of the class described, 70 a pair of receptacles, means including cables for moving said receptacles, a stationary support including a pair of pulleys, a flexible connection surrounding said pulleys and attached to said receptacles, a pair of 75 brakes for said pulleys, and means actuated by said flexible connection for simultaneously applying said brakes when a cable fails. 75

6. In an apparatus of the class described, 80 a stationary support, a pair of pulleys on said support, a cable trained over said pulleys and extending in the form of a loop between said pulleys, receptacles attached to the ends of said cable, brakes for said 85 pulleys, a rotary device mounted in said loop and having means for actuating said brakes, and operating means for said receptacles. 85

7. In an apparatus of the class described, 90 oppositely movable members, power means, connections between said power means and members for moving the latter in opposite directions, independent sustaining means for said members comprising stationary rotary devices, brakes for said rotary devices, and means for applying said brakes when one of said connections fail. 90

8. In an apparatus of the class described, 95 oppositely movable members, a safety cable attached to said members, supporting means for said cable, movable braking means for said supporting means and means operated by said cable for actuating said braking means when said cable sustains said members. 100

In testimony whereof I have hereunto subscribed my name.

CARL FREEMAN BLEDSOE.
